DESIGN FOR A COMBINED RECEPTACLE AND COVER THEREFOR

Walter T. Stopa, Chicago, Ill., assignor to Edison
General Electric Appliance Company, a corporation of New York

Application December 14, 1938, Serial No. 81,781

Term of patent 14 years

To all whom it may concern:

Be it known that I, Walter T. Stopa, a citizen of the United States, residing at Chicago, in the county of Cook, State of Illinois, have invented a new, original, and ornamental Design for a Combined Receptacle and Cover Therefor, of which the following is a specification, reference being had to the accompanying drawing forming a part thereof.

The figure is a perspective view of a combined receptacle and cover therefor showing my new design.

I claim:

The ornamental design for a combined receptacle and cover therefor, as shown.

WALTER T. STOPA.
